UNITED STATES PATENT OFFICE.

FREDERICK WILFRID SCOTT STOKES, OF LONDON, ENGLAND, ASSIGNOR TO WILLIAM S. PEIRCE, TRUSTEE, ACTING CHIEF OF ORDNANCE, UNITED STATES ARMY.

PROJECTILE.

1,313,926.

Specification of Letters Patent. Patented Aug. 26, 1919.

Application filed May 13, 1916. Serial No. 97,389.

To all whom it may concern:

Be it known that I, FREDERICK WILFRID SCOTT STOKES, a subject of the King of England, residing at London, in England, have invented certain new and useful Improvements in Projectiles, of which the following is a specification.

This invention relates to projectiles and has for its object to produce a projectile 10 of simple construction which can be cheaply made and is more especially intended for use in guns of the howitzer type such as trench mortars and the like.

According to this invention the projectile 15 has a hollow body on the rear end of which is formed or mounted a tubular open ended extension of less diameter than the body which constitutes a chamber adapted to contain an explosive propellant cartridge. 20 The wall of the tubular cartridge chamber is perforated with holes of such dimensions and in sufficient number to permit of the passage therethrough of the products of combustion when the charge is fired after 25 providing for a sufficient pressure inside the walls of the cartridge case to insure a good and regular combustion of the propellant charge. The projectile may be formed with one or both ends integral with the body 30 but a preferred arrangement is to construct a hollow cylindrical body and separate end plates or members each of which is secured in place at the end of the cylindrical body by forcing the plate on or into the open end 35 of the latter with a comparatively soft metal ferrule interposed.

The cartridge which is to be placed in the tubular chamber is conveniently similar to the cartridges ordinarily employed 40 with sporting shot guns having a metallic head which carries a percussion cap. The cartridge is charged, however, with an explosive suitable to the purpose set forth, for example such as that known as ballis- 45 tite.

The body of the projectile is filled with some high explosive material adapted to be fired either by a time or by a percussion fuse. The construction and arrangement of 50 this fuse may vary but preferably it is controlled by a safety device of such a nature that the arming of the fuse will not take place and the fuse be changed from a state of safety if the projectile is thrown only 55 a short distance from the muzzle of the gun.

in consequence of the partial failure of the propellant charge.

The fuse whether of the time or percussion type may be disposed in a head of suitable shape constructed of aluminium or 60 other material and mounted on or formed in one with the plate or end which constitutes the forepart of the projectile.

The propellant charge disposed as described in a separate cartridge is not inserted in the chamber on the projectile base until the projectile is to be used. The gun with which the improved projectile is mainly intended to be employed is provided with a smooth bore and of such 70 diameter with relation to that of the projectile that the latter is an easy fit in the bore and will readily slide down into the breech of the gun when it is to be discharged, the gun barrel being mounted for 75 the purpose with its axis at a considerable angular elevation. The propellant charge carried on the base or rear end of the projectile is fired by impact with a striker mounted in the breech of the gun. It may, 80 however, be fired by inserting the projectile in the breech chamber and operating a movable striker.

In the accompanying drawings which illustrate by way of example projectiles 85 constructed in accordance with this invention:—

Figure 1 is a longitudinal sectional elevation of one of the improved projectiles provided with a time fuse; 90

Fig. 2 is a similar view of the fore end of an improved projectile provided with a percussion fuse;

Fig. 3 is a longitudinal sectional elevation of a modified form of the improved 95 projectile provided with a time fuse;

Fig. 4 is an elevation of the rear end of the projectile shown in Fig. 3.

Like letters indicate like parts throughout the drawings.

Referring to Fig. 1 the projectile comprises a hollow cylindrical body A with open ends adapted to be closed by end pieces. The rear end piece B has a boss B' provided with a screw-threaded hole into 105 which is screwed a tubular member C with open end. The wall of this tubular extension C is perforated as at C' and the internal diameter of the tubular chamber is such as to enable a cartridge, as indicated 110

- in dotted lines at D, to be inserted therein. This cartridge is similar to those ordinarily employed with sporting shot guns, being composed of a metallic head with flange 5 and percussion cap, which head lies in the open end of the tubular chamber C. The body of the cartridge D is composed of brass, cardboard or other similar material not easily torn when the cartridge is exploded. The dimensions and number of the holes C' in the wall of the cartridge chamber C are such as to permit the gases of explosion to pass therethrough with fair freedom while at the same time sufficient 10 support is given to the wall of the cartridge itself before perforation to insure an efficient and regular explosion of the charge. Such charge may conveniently be composed of ballistite or other like composition.
- 20 On the face of the end piece B opposite to that which carries the cartridge chamber C is formed a projecting flange B² of such dimensions as will easily enter the end of the hollow projectile body A. A ferrule E of 25 suitable comparatively soft metal, such as lead, is placed over the face of the end piece B and flange B² and the end piece is then pressed into the end of the body A where it is held by friction.
- 30 The fore end of the projectile body A is closed in a similar manner to the rear end by an end piece F provided with a flange F' between which and the end of the body A is interposed a soft metal thimble E' so that 35 this fore end piece when pressed into place is frictionally held there.
- The fore-end piece F carries a suitably shaped head in which is disposed either a time fuse or a percussion fuse for the purpose of firing the charge of high explosive with which the hollow body A is filled. The time fuse illustrated in Fig. 1 is constructed on known lines as to its principal features but the device for arming the fuse 40 is novel and will be presented in another application. In the head G is formed a central longitudinal passage G' in which is a hammer H which when released can slide under the action of a spring H' and strike a per-
- 45 cussion pellet J. The latter is carried by a screw threaded nipple K which serves to connect the head G to the end piece F. In this nipple is a passage K' containing a short piece of "Bickford" fuse Q which is 50 ignited by the percussion cap J, which in turn ignites the detonator Q' which explodes the contents of the shell body. The passage K' communicates with the interior of the hollow projectile body A through the detonator tube F⁴. The hammer H is held inoperative by a two-armed lever L L' pivotally mounted at L² on the head and having its short end L' shaped to engage the end H² of the hammer. The long arm L of the 55 lever has its end bent inward and formed

so as to be engaged by the end of a sliding pin M mounted in a hole formed in the head G parallel to the axis of the projectile. The end of the pin is conveniently reduced so as to enter a hole formed in the end of the lever L. A spring M' disposed behind the pin M tends to force this pin forward, that is to say outward and keep its end in engagement with the end of the lever L. A safety pin N which lies in a hole bored 75 through the head H engages an annular recess M² formed in the sliding pin M and prevents movement of the latter until the safety pin N is withdrawn.

In operation when the projectile is to be 80 fired the safety pin N is withdrawn and a cartridge is inserted in the chamber C. The projectile is now inserted in the gun and the cartridge fired, preferably by allowing the projectile to slide down the smooth bore 85 of the gun which is arranged at a considerable inclination to the horizontal so that the cap of the cartridge is detonated by a striker mounted in the breech of the gun. If the shock of discharge is of full force it 90 is sufficient to cause the pin M by reason of its inertia to move rearward against the action of the spring M' when the end of the lever L is released. On leaving the gun this lever immediately turns about its pivot 95 L² owing to the action of the spring H' and the hammer H is then released and by the action of the same spring caused to strike the percussion pellet J with the result that the Bickford fuse composition is ignited 100 and the charge within the projectile is then in due course exploded by the detonation. If from any cause, such for example as the complete or partial failure of the charge in the cartridge D the shock of discharge is 105 either insufficient to throw the projectile a safe distance from the muzzle of the gun or even not eject it at all, then such shock will not suffice to cause the inertia of the pin M to overcome the action of the spring 110 M', to the extent necessary to effect the release of the lever L. When this occurs the projectile is harmless and will not explode as it falls.

The projectile is intended to be fired from 115 a smooth bore gun within which it is an easy fit.

The percussion fuse illustrated in Fig. 2 is so constructed that it will be armed in the same manner by the rearward movement of spring pins M as the time fuse. In the construction of this percussion fuse the end piece F is made of sufficient dimensions as to permit of its having formed in it a hollow F² which is closed by a partially hollowed cap F³ held 120 in place by set screws or otherwise as found convenient. The hollow F² is preferably spherical or approximately so and adapted to receive an approximately spherical body O which constitutes the hammer of the fuse. 125 130

- The body O is hollowed out as at O' and from this central cavity lead a number of radial passages O² at the outer end of each of which is mounted a percussion cap O³.
- 5 In a larger radial passage lies one end of a strip of instantaneous fuse material Q, the other end of which is carried down into a detonator Q' disposed in the inner end of a tube F⁴ mounted centrally in the end piece F.
- 10 F. The end of the tube F⁴ with the detonator Q' lies within the hollow shell body A and in contiguity with the explosive charge therein. Running right through the spherical hammer body O on a diameter thereof
- 15 which is preferably at right angles to the direction in which the fuse strip Q is led, is a passage in which is disposed a coiled spring R each of whose ends bears against the inner end of a safety bolt S. Each of these
- 20 bolts has formed in it toward its outer end an annular recess S' adapted to be engaged by the end of one of the spring pins M in the manner shown in Fig. 2. These outer ends of the safety bolts S lie in open ended passages formed in the end piece F
- 25 so that when the spring pins M set back on discharge of the projectile and are disengaged from the safety pins S, the latter are free to move outwardly under the influence of the spring R and be thrown out or moved sufficiently to release the hammer body O. The latter is then left free within the cavity F². When now the projectile makes impact with an object, the hammer body O is thrown
- 30 against the wall of the cavity F² and one or more of the caps O³ is detonated. This detonation passing through the radial passage O² into the central cavity O' ignites the fuse Q and so fires the detonator Q' and explodes
- 35 the charge within the shell.
- 40 It will be seen that here also if the shock of discharge from the gun is not of full force the pins M will not set back sufficiently to release the safety bolts S and the hammer body will then continue to be held rigidly by these bolts and explosion of the shell will not occur on impact.
- 45 It is to be noted that the time and percussion fuses more particularly described above are only set forth as examples of constructions in conjunction with which the spring pins M may be employed. This spring pin device may be utilized in other ways to effect the arming of fuses of other type.
- 50 Figs. 3 and 4 illustrate a modified construction of projectile in accordance with this invention and provided with a simple type of time fuse. In this case the shell body A is cast hollow with its base A' integrally as also the head A². In the latter is formed a hole through which the explosive charge can be filled into the body of the shell, this hole being subsequently closed by a screw plug A³. In the base A' is formed
- 55 an annular recess A⁴ from which a passage A⁵ leads into the interior of the shell. In the recess A⁴ is placed a length of "Bickford" fuse (not shown on the drawing) with one end carried down into the passage A⁵ so that there is formed an annulus of 70 fuse material which when ignited at any point in the circle will burn at a known rate and in due course either ignite a detonator disposed in the shell or directly explode the charge within the shell. The annulus A⁴ is 75 covered in by a rotatable time disk T which is held in place by the tubular cartridge chamber C, whose forward end is reduced and screw-threaded as at C², this part being passed through a central opening in the disk 80 T and screwed into the base plate A'. A hole T' is formed in the time disk T at such a radial distance from the center of the disk that this hole will lie over the recess A⁴. The periphery of the disk T is graduated so 85 that it can be rotated and set in a known relation to a mark on the base A'. Conveniently the hole T' is covered by some material which can be torn away or perforated.
- 90 When the projectile is to be discharged the covering over the hole T' is destroyed and the Bickford fuse is pierced by inserting a suitable pointed instrument through the hole T'. The disk T is set by the graduations in accordance with the time that it is intended to elapse between the discharge of the projectile and its explosion. The projectile is now placed in the gun and fired in some convenient manner such as that already described. The flash from the explosion of the cartridge in the chamber C passes out of this chamber through the holes C' and ignites the fuse in the recess A⁴ through the puncture opposite the hole T'. The fuse 100 now burns around the annulus and in due course fires the detonator or directly brings about the explosion of the shell.
- 105 What I claim as my invention and desire to secure by Letters Patent is:—
- 110 1. A projectile having a cylindrical body and a base having a receptacle for a propelling charge, said receptacle being rigid with the base, of less diameter than the projectile, and extending rearwardly therefrom and having its outer end open to receive a propelling charge and its lateral wall perforated to permit of the escape of the propelling gases into the space surrounding the receptacle in rear of the projectile.
- 115 2. A projectile having a cylindrical body and a base having a receptacle for a propelling charge, said receptacle being rigid with the base and extending rearwardly therefrom and having its outer end open to receive a propelling charge and its lateral wall 120 perforated to permit of the escape of the propelling gases into the gun barrel in rear of the projectile, in combination with a cartridge of propelling material fitting said re- 125
- 130

ceptacle, the lateral wall of said cartridge being adapted to yield on firing to permit the gases to expand through said lateral openings.

- 5 3. A projectile having a cylindrical body and a base having a rearwardly projecting receptacle for a cartridge, the said receptacle being rigid with the base and of substantially less diameter than the projectile and
- 10 having its outer end open to receive a cartridge, and its lateral wall perforated to permit of the passage of the gases from the

cartridge into the gun barrel in rear of the projectile, in combination with a cartridge of explosive material fitting within said receptacle. 15

In witness whereof I have signed my name to this specification in the presence of two subscribing witnesses.

FREDERICK WILFRED SCOTT STOKES.
